UNITED STATES PATENT OFFICE

JOSEPH R. BLAINE, OF OAK PARK, ILLINOIS, ASSIGNOR TO MIEHLE PRINTING PRESS & MANUFACTURING COMPANY, OF CHICAGO, ILLINOIS, A CORPORATION OF ILLINOIS

REGISTER DETECTOR

Application filed May 3, 1924. Serial No. 710,755.

This invention relates to printing presses and more particularly to front register detector mechanism therefor.

One object of the invention is to provide simple, reliable and efficient detector means which will automatically trip the press if a fed sheet is not properly registered or if no sheet is fed.

Another object is to provide simple means for preventing constant tripping action of the parts after the press is once tripped, thereby preventing actuation of the parts involved.

Another object is to provide simple means to prevent tripping action on the "off" revolution of a two revolution type of press.

Another object is to provide printing press detector and tripping mechanism adapted to meet all of the requirements under service conditions.

These and other objects are accomplished by means of the arrangement disclosed on the accompanying sheets of drawings, in which—

Figure 1 is a fragmentary side elevation, parts being in section, of a printing press embodying my invention;

Figure 2 is an enlarged fragmentary side view, parts being in section, of the impression cylinder and associated detector and trip mechanism;

Figure 3 is a view taken in the plane of line 3—3 of Figure 2;

Figure 4 is a detail top plan view of the detector mechanism; and

Figure 5 is a sectional view taken in the plane of line 5—5 of Figure 4.

The various novel features of the invention will be apparent from the following description and drawings, and will be particularly pointed out in the appended claims.

The invention is illustrated in connection with what is known as a two revolution type of press in which the cylinder 10 makes two revolutions for each printing cycle. The impression cylinder 10 not only rotates, but has a vertical reciprocating movement, there being one complete down and up movement for two revolutions of the cylinder. Each of the cylinder journals 11, only one of which is shown, is mounted in a journal box 12 which

falls and rises with the cylinder. A sheet at a time is fed down over the feed board 13 of the press toward the cylinder 10, the forward feeding movement of the sheet over the feed board 13 being temporarily stopped by a plurality of front guide stop members, only one, 14, of which is shown. This stop member is carried by a bracket 15 which in turn is secured to a shaft 16 to which an arm 17 is secured having a roller 18 cooperating with the cam 19 for automatically raising the front guide stop 14 at the proper time in the cycle or, in other words, at the time that cylinder grippers grip the sheet preparatory to causing an impression to be made. Guide means 20 is secured to the front stop 14 for directing the paper to the lower edges of the front stops 14. Also mounted on the front guide stop 14 is a sheet or front register detector including a finger 21 secured to a bracket 22 pivotally mounted at 23 on the front guide stop 14. In this connection it will be noted that when the front guide stop 14 is raised to permit the passage of a fed sheet thereunder, the guide means 20 and front detector means 21 also rise with the front guide stop 14. Secured to the finger pivot 23 and extending therefrom is a hook 24 which cooperates with a shouldered portion 25 on a spring pressed slide bar 26, said bar having a second shoulder or projection 27 which cooperates with a finger 28 mounted to oscillate with a rock shaft 29, the spring 37^a tending to force the bar toward the left as viewed in Figures 2 and 4. As shown in Figure 1 of the drawings, the detector finger 21 has been moved forwardly by a sheet 30, causing the detector 22 to rotate in a clockwise direction for raising the hook 24 out of engagement with, or out of the path of movement of the shouldered portion 25 on the spring pressed slide bar 26. Under such conditions, that is, when the hook 24 is raised the fed sheet will receive its impression and the press will not be tripped. However, if no sheet is fed or a fed sheet is not properly registered with respect to the front guide stops 14 the front detector fingers 21 will not be moved, but will remain as shown in Figure 2, with the results that the hook 24 will not

be raised and the press will be tripped by mechanism to be considered hereinbelow.

The tripping connection includes an arm 31 secured to the rock shaft 29 to which arm 5 one end of the link 32 is pivoted, the other end of which link is pivoted to one arm 33 of a three-armed bell crank lever 34 pivoted to a frame part at 35. The link 32 passes through an aperture in a guide support 36, against the under-surface of which a spring 37 coiled around the link abuts, the opposite end of the spring 37 pressing against a collar 38 on the link 32, the effect being that the spring 37 tends to rock the shaft 29 and accordingly 10 tends the pin 28 in a clockwise direction, as viewed in Figures 1 and 2, so that a roller 39 carried in a second arm 40 of the bell crank lever 34 may be pressed against and follow a cam 41 rotatable with the journal 11. The third 15 arm 42 of the bell crank lever 34 is pivotally and slidably connected to a link 43 which in turn is connected to a movably mounted bar 44 one end of which is pivotally connected to one arm 45 of a bell crank lever 46, the 20 other arm 47 of which is connected to a link 48 which in turn is connected to a bell crank lever 49 having one arm with a hook 50 normally preventing a clockwise movement of a lever 51 pivoted at 52 and bearing upon an 25 other lever 53 secured to a rock shaft 54 which is connected to the ultimate parts for tripping the press. A spring 55 presses downwardly upon the lever 51, tending to trip the 30 press and a lighter spring 56 holds the lever 35 53 in a predetermined position and also holds up a trip pedal 57 connected to the lever 53. A second manual trip lever 58 is provided at the point where the arm 47 is operatively connected to the link 48. It will be noted that 40 the bar 44 has a shoulder 59 which at times is engaged by a projection 60 on a plate 61 adjustably secured to the journal 11. The plate 61 of course moves vertically up and down with the journal 11 in addition to rotating 45 therewith. From the arrangement described, it will be apparent that whenever the projection 60 in its counterclockwise rotation engages the shoulder 59 the bar 44 will be shifted to the left, as viewed in Figure 2, for causing 50 a tripping of the press through the connections hereinabove described. If the shoulder 59 is removed from the path of movement of the projection 60 before the projection reaches that point of its cycle of rotation, the 55 tripping connections will remain undisturbed and the press will not be tripped. In this connection the detector hook 24 has a direct relation with respect to the bar 44, for if the detector hook 24 is raised, the bar 23 will be 60 permitted to slide to the left under the tension of spring 37^a and the rock shaft 29 will be permitted to rotate a given amount in a clockwise direction, and the bell crank lever 34, under the tension of the spring 37, will be 65 permitted to rotate a given amount in a coun-

ter-clockwise direction for permitting the roller 39 to follow the cam 41 and for positively raising the bar 44 and accordingly, its shoulder 59 out of the path of movement of the projection 60. In other words, under 70 the conditions described, with the detector hook 24 raised the shoulder 59 will be raised out of the path of movement of the projection 60 for preventing the tripping of the press. On the other hand, however, if the detector 75 hook 24 is not raised, due to no sheet being fed, or improper front register, the bar 44 and, accordingly its shoulder 59, will not be raised out of the path of movement of the projection 60 and the bar 44 will be thrust to the 80 left for tripping the press through the connections described.

When the press is once tripped, it remains tripped until reset, by depressing pedal 70, for the purpose of preventing useless tripping actions and the consequent wear of parts involved. It is understood, of course, that the spring 55 is the element which holds the right hand ends of the trip levers 51 and 53 down and accordingly maintains the hook 50 85 ineffective. But the wear of parts referred to are those parts including the projection 60, shoulder 59, and other cooperating members from there to the detector finger 21. With respect to the holding of parts in tripped position when the press has been tripped, attention is called to the fact that the left hand end of the bar 44 is provided with a shoulder 61^a which, when the bar 44 is thrust to the left, engages a projection 62 on the lever arm 40 for preventing said lever arm 40 from moving in a counterclockwise direction and accordingly preventing the roller 39 from passing into the depressed portion of the cam 41. If, under trip conditions the roller 39 were permitted to pass into the depressed portion of the cam 41, it will be appreciated that the bar 44 would then be raised and shortly thereafter again lowered so that the shoulder 59 would again pass into the path of movement of the projection 60 which in turn would cause a second tripping action of those parts in spite of the fact that the press already is in tripped condition. It is the useless tripping actions and the consequent wear of said parts, 100 after the press has been tripped, which the shoulder 61^a on the bar 44, and lug 62 on arm 40, prevents.

Additional means are provided to prevent a tripping action on the "off" revolution of the cylinder, it being understood that the cylinder makes two revolutions in a single printing cycle. The means referred to includes a lug 63 on the inner side of lever arm 40 and a lug 64 on the outer side of journal 12. As shown in Figure 2 of the drawings, the cylinder 10 is in its up position and the lugs 64 and 63 are out of horizontal alignment and said lugs are not functioning. However, when the cylinder moves downwardly on its 115 120 125 130 135

"off" revolution, the lug 64 passes into horizontal alignment with lug 63, thereby preventing a counterclockwise movement of the lever arm 40 and preventing tripping action 5 of the parts. At this time the plate 61 is in its lowered position and accordingly projection 60 does not engage shoulder 59, it being understood that plate 61 moves up and down with journal 11. This lug arrangement including the lugs 64 and 63, together with the up and down movement of the cylinder, accomplishes exactly what a two to one reduction gear would accomplish without additional gearing, and by means of this arrangement the use of reduction gearing is avoided.

To summarize the operation of the press; as has already been stated the press shown is of the two revolution type, wherein there are two revolutions of the cylinder 10 for each 20 printing cycle, a cycle including a vertical reciprocation, or an up and down movement of said cylinder. It will be appreciated that when the cylinder is down the sheet 30 receives its impression and the press is not 25 tripped, tripping of the press causing the cylinder to remain in up position, wherein no impression is made on the sheet. Sheets 30 are fed one at a time over the board 13 toward the cylinder 10, but come in contact 30 with and are stopped temporarily by the stop members 14. At the proper time in the cycle, that is, when the cylinder is in up position, cam 19 revolving with the cylinder 10 operates the arm 17 to automatically raise the 35 front stop members 14 at which time the cylinder grippers grip the sheet preparatory to causing an impression to be made, which impression can then be made on the next revolution wherein the cylinder is in down 40 position. In this connection, when the sheet is fed down over the board 13, it will contact the fingers 21 moving the same to thereby cause the hook 24 to be raised, at which time the sheet will be moved with the cylinder and 45 will receive its impression, the cylinder being in down position, and the press will not be tripped. However, if no sheet is fed, or if the sheet is so fed as not to register with the front guide stops 14, fingers 21 will not be 50 moved, but will remain in the position as shown in Figure 2, with the result that the hook 24 will not be raised and the press will be tripped, that is, the cylinder 10 will not be permitted to reciprocate, but will merely rotate in up position. When such operation occurs, that is, when the hook 24 is not freed or not raised, the cylinder in revolving will cause the projection 60 on the plate 61 to 55 come in contact with the shoulder 59 on the bar 44 to move said bar toward the left as viewed in Figure 2, which will operate through the bell crank 46 to raise the link 48 to free the hook 50 of the bell crank lever 49 from its engagement with the lever 51. The 60 spring 55 will then depress the levers 51 and

53 in a clockwise direction to trip the press and the press will remain tripped until reset by depressing the pedal 70 to thereby cause engagement between the hook 50 and the lever 51, spring 56 maintaining lever 53 in normal position when the press is not tripped. When the press is once tripped, the shoulder 61^a of the lever 44 is thrust to the left and engages a projection 62 on the inside of the lever arm 40, which will prevent the arm 40 from moving in a counter-clockwise direction, and accordingly will prevent the roller 39 from passing into the depressed portion of the cam 41, it being understood that the cams 41 and 19 are in the relative position as indicated in Figure 2. By preventing the roller from following the cam 41, bar 44 is prevented from being raised and lowered so that the shoulder 59 will not again be operated by the projection 60, so that these parts will not perform a tripping function in spite of the fact that the press is in tripped condition. This mechanism then eliminates useless tripping action of the parts and consequent useless wear.

It will be appreciated that it is not desirable to have a tripping action when the cylinder is down or on the off revolution, and for this reason, when the cylinder moves downwardly, the lug 64 on the outer side of the journal box 12 passes into horizontal alignment with the lug 63 on the inner side of the lever 40 to thereby prevent a counter-clockwise movement of the lever arm 40 to thereby prevent tripping action of these parts. At this time the plate 61 is in its lowered position and accordingly projection 60 does not engage shoulder 59. Under normal action, that is, where the sheet 30 is correctly fed, causing the hook 24 to be raised, permitting the cylinder grippers to move the sheet for its impression in the downward position of the cylinder when the hook 24 is raised it releases the slide bar 26, in which case the shaft 29 may rotate in a clockwise direction to permit the arm 40 to follow the cam 41, which will raise and lower the bar 44 to prevent tripping action of the parts until some condition prevails, such as incorrect feeding of the sheet to cause tripping operation of the parts as already described.

In interpreting the claims in which the expression "trip control member" is used, the bar 44 is referred to and where the expression "reciprocating member" or "slide member" is used, the member 26 is referred to.

It is my intention to cover all modifications of the invention falling within the spirit and scope of the following claims.

I claim:

1. In a printing press, the combination of a guide stop member, a slide member movably associated therewith, and a detector operatively associated with said slide member whereby when said slide member and detector

are operatively connected tripping of the press results.

2. In a printing press, the combination of a guide stop member, a slide member movably associated therewith, and a detector operatively associated with said slide member whereby when said slide member and detector are operatively connected tripping of the press results and when disconnected the press 10 will be permitted to continue uninterrupted.

3. In a printing press, the combination of a guide stop member, a detector associated therewith, tripping means associated with said detector, said detector having a detector 15 finger and a hook portion, a slide member operatively associated therewith, and means associated with said detector whereby when said detector is not engaged or not properly engaged by a sheet the hook remains in operative association with said slide member, controlling said tripping means to cause tripping of the press.

4. In a printing press, the combination of a trip control member, rotatably mounted 25 means for actuating said trip control member for tripping the press, and means for preventing said trip control member again being given a tripping action until the press is reset.

5. In a printing press, the combination of a cylinder, a trip control member, a member rotatable with said cylinder and operable upon said trip control member for moving the latter for tripping the press, and means 35 for preventing said trip control member taking a position in which it may be given another tripping action until after the press has been reset.

6. In a printing press, the combination of a trip control member, a bell crank lever, a connection therebetween whereby said trip control member may be actuated, and means for giving said trip control member a different movement for tripping the press, said bell 45 crank lever and trip control member having cooperating means for preventing said trip control member taking the position wherein it is subject to a second tripping action until after the press is reset.

7. In a printing press which has a cylinder having two revolutions to a single printing cycle, a journal box in which the journal of said cylinder is supported, and a lever cooperating with the tripping mechanism for the 55 press, said journal box and lever having cooperating means thereon to prevent tripping action of parts of the press during the off revolution of the cylinder.

8. In a printing press which has a cylinder 60 having two revolutions to a single printing cycle, a journal box in which the journal of said cylinder is supported, a lever forming a part of the tripping connection for the press, said journal box and lever having cooperating 65 means to prevent tripping action of parts of

the press during the off revolution of the cylinder, and a trip control member operatively associated with said lever, said trip control member and lever having cooperating means to prevent continued tripping action of the 70 tripping parts after the press has been tripped and until the press has been reset.

9. In a printing press having a reciprocating cylinder, tripping mechanism associated with said cylinder, and means associated with said tripping mechanism and reciprocating with said cylinder for preventing tripping action of parts of the press on the off revolution. 75

10. In a printing press, the combination of a cylinder having two revolutions to a single printing cycle, tripping mechanism associated with said cylinder, and means including cooperating reciprocating and oscillating members for preventing tripping action of 80 parts of the press on the off revolution. 85

11. In a printing press, the combination of a cylinder having two revolutions to a single printing cycle, tripping mechanism associated with said cylinder, and means associated with said tripping mechanism and reciprocating with said cylinder for controlling tripping of said press. 90

12. In a printing press, the combination of a cylinder having two revolutions to a single printing cycle, tripping mechanism associated with said cylinder, means including cooperating reciprocating and oscillating members for controlling tripping action of 95 said press, and means on one of said last 100 named members cooperating with the other of said last named members for preventing consecutive tripping of said press.

13. In a printing press, the combination of a reciprocating cylinder having two revolutions to a single printing cycle, a movable journal box for a journal of said cylinder, means controlled by said cylinder to permit printing, cooperating members associated with said means, one of said members having operative association with a trip control member, the other of said members being actuated upon incorrect feeding to said cylinder, means associated with said cylinder for operating said trip control member to trip said press, resetting means for resetting the press and returning the trip control member to operative position, and cooperating means associated with said journal box and first named cooperating members to prevent consecutive tripping of said press. 110 115 120

14. In a printing press, the combination of a reciprocating cylinder having two revolutions to a single printing cycle, a movable journal box for a journal of said cylinder, means controlled by said cylinder to permit printing, cooperating members associated with said means, one of said members having operative association with a trip control member, the other of said members being 125 130

actuated upon incorrect feeding to said cylinder, means associated with said cylinder for operating said trip control member to trip said press, resetting means for resetting the press and returning the trip control member to operative position, and cooperating means associated with said first named cooperating members and said trip control members to prevent tripping action of parts of said press on the off revolution.

Signed at Chicago, Illinois, this 8th day of April, 1924.

JOSEPH R. BLAINE.
